UNITED STATES PATENT OFFICE.

HARRY TIEKE, OF OAKLAND, CALIFORNIA.

BARREL-FILLING STAND.

1,369,856.

Specification of Letters Patent.

Patented Mar. 1, 1921.

Application filed June 10, 1920. Serial No. 387,993.

To all whom it may concern:

Be it known that I, HARRY TIEKE, a citizen of the United States, residing at 969 63d street, Oakland, in the county of Alameda, State of California, have invented a new and useful Barrel-Filling Stand, of which the following is a specification in such full and clear terms as will enable those skilled in the art to construct and use 10 the same.

This invention relates to a barrel stand used for the purpose of holding barrels, casks or drums at the proper elevation for filling, and its object is to produce a stand 15 which is capable of holding either drums or barrels as the case may be.

It will be understood by those skilled in the art that where a number of drums, casks or barrels are filled that there will be 20 different kinds of barrels and drums some to be filled on the side and some to be filled through an opening in the end.

Where the drums are to be filled from the side, it is necessary to hold them in a fixed 25 position while being filled, while the stand for holding the drums is not suitable for holding barrels to be filled from the end, but the two stands must be capable of immediate and interchangeable use, since the 30 barrels, casks and drums alternate progress to the attendant at the filling stands.

Other objects of the invention will appear as the description proceeds.

An embodiment of the invention is shown 35 in the accompanying drawings in which the same reference numeral is applied to the same portion throughout, but I am aware that there may be modifications thereof.

Figure 1 is a side elevation of the complete apparatus.

Fig. 2 is a plan view of the complete apparatus.

Fig. 3 is a side elevation of the stand as it appears when used for filling a barrel on 45 the end.

The stand comprises a holding base 1, with a couple of steel wear plates 2 and 3 on its upper side. Hinged to the base 1 are two skids 4 and 5, said skids being connected by means of cross bars 6, 7 and 8. 50 The skids are provided with a depression 9 in their tops to hold the drum steady and they have steel binding plates 10 and 11 to prevent undue wear of the sloping ends.

Connected with the skids and with the 55 base are two stiff springs 12 and 13 which serve to normally hold the skids upright in the position shown in Fig. 3. However, when the drum is to be filled, the skids are turned down as shown in Fig. 1.

A hook 14 serves to hold the skids down when a drum is to be moved thereupon, and said hook has a spring 15 to hold it in a position to be engaged with the projecting end of the cross piece 7, while a 65 foot piece 16 enables an attendant to release the hook and allow the skids to spring up to the position shown in Fig. 3, whenever he has to fill the short barrel.

Cleats 17 and 18 are used to connect the 70 springs 12 and 13 to the stand and skids respectively.

What I claim is as follows, but various modifications may be made in the construction shown in the drawings and above particularly described form, within the purview of my invention:

A two level barrel stand comprising a raised base, a pair of skids hinged to the base, springs for holding the skids normally raised substantially at right angles to the base, and a latch for securing the skids horizontally against the base.

In testimony whereof I have hereunto set my hand this 20th day of March, A. D. 85 1920.

HARRY TIEKE.
